MOP WRINGER

Aaron Wenger, Bayonne, N. J.

Application December 5, 1932, Serial No. 645,720

10 Claims. (Cl. 15—262)

This invention relates to improvements in mop wringers of a class adapted to be supported by a pail or bucket and the floor upon which the bucket rests, without being secured to the bucket.

5 This application covers an improvement over the invention covered by my application Ser. No. 563,032 filed September 16, 1931.

One of the objects of my present invention is to provide a mop wringer wherein the force employed to squeeze or wring out a mop is adapted to be applied through pressure directed substantially downward at a point between the supporting floor and bucket.

Another object is to construct such a wringer so that an operator may stand on it to exert the maximum available wringing pressure without danger of moving or upsetting the bucket notwithstanding said bucket is not secured to the floor and the wringer is not secured to the bucket.

20 Another object of the invention is to provide a device of this kind in which the application of great wringing pressure may be applied to a mop through a pair of wringer rollers and the mop withdrawn therefrom without tending to slide the bucket along the floor or upset the same.

Another object of my invention is to provide a device in which the wringing rollers are adapted to stop short of contacting with one another when they are pressed into wringing position and 30 prevent the mop from being immovably clamped between the rollers.

Another object of the invention is to provide a device of the class described with means for varying the wringing position of the rollers with respect to each other according to the thickness 35 of the mop and prevent the wringing rollers from immovably clamping a mop between them.

Another object is to provide a mop wringer of the class described comprising treadle means for 40 opening said device to receive a mop and treadle actuated cam means upon which an operator may stand to hold the wringer and bucket upon the floor to press the mop so that the same will be wrung out upon withdrawal therefrom, said 45 cam means being adapted to limit the extent to which the device may be opened.

These and other objects of my invention will 50 become apparent or be specifically referred to in connection with the following description of my invention and the drawing referred to therein, in which

Figure 1 is a side elevation of my mop wringer with a mop inserted therein and showing the foot of an operator about to squeeze the mop between 55 a pair of wringing rollers before wringing out the

mop by the withdrawal thereof from between said rollers.

Figure 2 is a plan view of the device shown in Figure 1.

Figure 3 is an enlarged detailed view showing 60 the manner of mounting the wringing rollers and the cam means for pressing the same together.

Figure 4 is a sectional view similar to that shown in Figure 1 except that it incorporates 65 a device adapted to limit the movement of the wringer rollers toward each other to accommodate a mop of larger size than that shown in Figure 1.

Figure 5 shows a fragmentary view of the 70 wringer shown in Figure 1 and illustrates the manner in which the opening movement of the device is limited by the cam means for closing the same.

Referring now to Figure 1, it will be seen that 75 my mop wringer comprises a base frame 10, one end of which is adapted to rest upon, and be supported by, a rim 11 of a bucket or pail 12 and the other end is adapted to rest upon the floor or bucket supporting surface. In the embodiment 80 of my invention illustrated in the accompanying drawing the frame 10 is essentially U-shaped with the closed end of the U, 13, adapted to rest upon the floor at a point somewhat removed from the bottom of the bucket. The sides 14 of the U-shaped frame 10 are formed to provide a horizontal portion 15 disposed between the closed end 13 and the bucket. At one end of the portion 15 the sides 14 are bent upwardly toward the top of the bucket forming side portions 16. These side portions 16 are bent inwardly at 17 and 85 downwardly at 18 to form hooks adapted to extend into or hook onto the bucket to support the frame on the rim of the bucket. The side portions 16 are also formed to extend somewhat beyond the ends of the hooks 17—18 to afford supports 20 for a wringer roller 21, adapted to be revolvably mounted on a roller shaft 22 carried by the supports. From Figure 2 it will be seen that the ends of the supports 20 are disposed 90 within the rim of the bucket and that the roller shaft 22 does not come in contact with the rim of the bucket. This arrangement insures that water which is wrung out of the mop by the action of the rollers, to be hereinafter described, will 95 flow into the bucket. Moreover, inasmuch as there is no contact between the roller 21 or shaft 22 with the rim of the bucket, obviously any tendency to rotate the shaft 22 when the mop is withdrawn from between the rollers, as hereinafter 100 described, will not cause the frame to move along 105

110

the top of the bucket. A guard 23, having offsets 24, is secured between the supports 20 and adapted to serve the dual purpose of stiffening the sides 14 of the frame 10 to prevent the strands 5 of the mop from becoming tangled or wound around the roller 21 when the mop is positioned against the roller and between the offsets 24.

Within the base frame 10 above described is a second frame 30, which, in the embodiment illustrated herein, is also substantially U-shaped. This frame 30 is pivotally hinged or secured to the frame 10 at 31—31. The closed end of the frame 30 is designed to project a short distance beyond or behind the supporting end 13, of the frame 10 to form a treadle 32 for rotating the frame 30 on the hinges 31—31 to open the wringer. Side pieces 33 of the frame 30 are formed somewhat similar to the side pieces 14 of the frame 10 above described, whereby the frame 30 is adapted to fit and move freely within the frame 10 about the pivots 31—31. The ends of the sides 33 are bent inwardly over the rim of the bucket at 34 and thence toward the roller supports 20 to provide supports 35 between which the second roller 25 36 is rotatably mounted on a shaft 27, carried by the supports 35. It will be seen from Figure 5 that when pressure is applied to the closed end or treadle 32 of the frame 30, preferably by the foot of the operator, the frame will be rotated and the roller 36 lifted through an arc described 30 about the pivots 31 and away from the roller 21 until such opening movement is arrested by the cam means to be hereinafter described. When 35 the foot pressure is removed the frame 30 is adapted to fall by gravity toward the roller 21 and against a mop 38, as shown in Figure 1. I also provide a stiffening brace 39 mounted between the open ends of the frame 30, to prevent the frame from spreading. The guard 23, in addition 40 to the functions above described, serves also to stiffen the open ends of the frame 10.

I now provide a treadle actuated cam means for forcibly pressing the roller 36 toward the roller 21. This cam means comprises a pair of arms 40 45 pivoted by studs 41 to the frame 10 proximate the hooks 17—18 thereof. The arms 40 are formed to fit over studs 42 mounted on the side pieces 33 of the frame 30 and adapted to project generally to a position in front of the bucket and 50 above the support 13, as shown in Figures 1 and 2. A treadle 43 is secured between the ends of the arms 40 remote from the studs 41 which secure the arms to the frame 10.

From the above the operation of my device 55 will be readily understood by referring now to Figure 1 wherein the mop 38 is disposed between the rollers 21, 36, having been placed there by the operator after he had pressed downwardly on the end 32 to rock the frame 30 about the 60 pivots 31—31 and withdraw the roller 36 from the roller 21 sufficiently to permit said mop to be placed within the bucket against the roller 21 and between the offset portions 24 of the guard 23 whereupon the operator removes his foot from the end 32 to permit the frame 30 to drop by 65 gravity against the mop. The operator is now able to apply pressure with his foot to the treadle 43 with the result that the arms 40 are rotated about the studs 41 and adapted through cooperation with the studs 42 to cam the frame 30 and 70 roller 36 toward the roller 21 when the treadle 43 is moved to the position shown in dotted lines in Figure 1. It will be seen that the frames 10 and 30 above described are proportioned such 75 that the operator may stand on the treadle 43

when it is in the lowermost, or dotted line, position and his weight will be disposed between the points where the hooks 17, 18 engage the rim of the bucket and the end 13 rests upon the floor. When in this position, standing on the treadle 43, the operator may then pull the mop from between the rollers 21—36 to wring water from the same into the bucket. It will be observed that when the treadle is in its lowermost position it is disposed approximately midway between the horizontal portion 15 on the frame 10, and, in effect, forms a steady platform upon which the operator may safely stand without danger of upsetting the bucket. 80

In Figure 1 I have illustrated a mechanism adapted to wring out a mop of medium size. In Figure 4, however, I provide means for wringing out a mop of larger size by preventing the treadle 43 from being pressed downwardly through its full stroke, so to speak. This means comprises a stop 45 mounted on the frame 10 and adapted to be elevated when it is desired to wring out a large mop and it is not necessary, and even undesirable, to bring the rollers 21 and 36 as close together as it is when a smaller mop is being wrung out. It will be seen from Figure 4 that in order to vary the space between the wringing rollers according to the size of the mop which it is desired to wring out the stops 45 may be elevated to limit the downward movement of the treadle, 95 or turned downwardly to a position along the side of the frame 10, when it is desired to permit the treadle to move through its full stroke. 100

While I have described what now appears to me to be the preferred embodiment of my invention it should be understood that I regard the same as susceptible of modification without departing from the spirit of my invention or exceeding the scope of the appended claims. 110

What I claim is:

1. In a mop wringer, a pair of frame members, means for pivotally hinging said frame members together, one of said frame members comprising a limiting portion, and means for simultaneously supporting said member in operative position upon the rim of a bucket and upon a bucket supporting surface at a point spaced from the bottom of the bucket, a mop compressing member carried by each frame member, and cam means for pressing one of said mop compressing members into operative position toward the other member, said cam means comprising a treadle adapted to rest upon the limiting portions of said frame member to limit the movement of said mop compressing member toward the other member and carry the weight of an operator when said cam means is operated. 120

2. In a mop wringer, a pair of frame members, means for pivotally hinging said frame members together, one of said members comprising means for simultaneously supporting the same in operative position upon the rim of a bucket and a bucket supporting surface and with said pivot means spaced from said surface, a mop compressing member carried by each frame member, and treadle actuated cam means for moving one of said mop compressing members toward the other to operatively close said wringer, said other frame member being adapted to project beyond said hinge means to form a treadle for moving the aforesaid mop compressing member away from the other to open said wringer. 135

3. In a mop wringer, a pair of frame members, means for pivotally hinging said frame members together, one of said frame members comprising 140

- means for simultaneously supporting the same in operative position upon the rim of a bucket and a bucket supporting surface and with said pivot means spaced from said surface, a mop compressing member, carried by each frame member, and treadle actuated cam means for moving one of said mop compressing members toward the other to operatively close said wringer without moving said other mop compressing member with respect to either said bucket or supporting surface, said other frame member being adapted to project beyond said hinge means to form a treadle for moving one of said mop compressing members away from the other to open said wringer, said cam means being adapted to limit the distance through which one of said mop compressing members may be moved away from the other.
4. In a mop wringer, a pair of frame members in pivoted relation, a mop compressing member carried by each frame member, means on one of said members for supporting one end thereof upon the top rim of a bucket which is resting upon a surface and for supporting the other end thereof on the bucket supporting surface, treadle means for rocking the other frame member with respect to the first mentioned frame member to move one of said mop compressing members away from the other, and cam means for pressing said mop compressing members together.
5. In a mop wringer, a pair of substantially U-shaped frame members having the sides thereof pivoted to each other at points proximate the base portion of the U, a mop compressing member carried by each frame member adjacent the open end of the U, the base portion of one of said frame members being turned downwardly beyond the pivots to form a rest, and the other end of said frame member being formed with hooks adapted to engage the rim of a bucket, the base of said second frame member being formed to project beyond the pivots to form a treadle operatively disposed above the rest and adapted to move one mop compressing member away from the other, studs on said second frame member proximate the end thereof remote from said treadle, and treadle actuated cam means for pressing one of said mop compressing members toward the other, said cam means comprising arms pivoted respectively to the sides of the first mentioned frame member proximate the mop compressing member carried thereby, said arms being disposed respectively in operative position with respect to said studs and having a treadle carried by the other ends thereof whereby a downward pressure thereon is adapted to move one of said mop compressing members toward the other.
6. In a mop wringer, a pair of substantially U-shaped frame members pivoted to each other at points proximate the base portion of the U, the base portion of one of said frame members being turned downwardly beyond the pivots to form a rest and the other end of said frame member being bent to form hooks adapted to engage the rim of a bucket, a mop compressing member carried by each frame member adjacent the open end of the U, said frame member being bent to form a horizontal support between said rest and hooks, the base portion of said second frame member being formed to project beyond the pivots to form a treadle operatively disposed above the rest and adapted to move one mop compressing member away from the other, studs on said second frame member proximate the end thereof remote from said treadle, and treadle actuated cam means for pressing one of said mop compressing members toward the other, said cam means comprising a pair of arms each having one end pivoted respectively to a side of the first mentioned frame member, said arms being disposed in operative position with respect to said studs and having a treadle carried by the other ends thereof whereby a downward pressure thereon is adapted to move one of said mop compressing members toward the other until said cam treadle rests upon said horizontal support.
7. In a mop wringer, a pair of frame members, means for pivotally hinging said frame members together, one of said members comprising means for simultaneously supporting the same in operative position upon the rim of a bucket and a bucket supporting surface and with said pivot means spaced from said surface, a mop compressing member carried by each frame member, treadle actuated cam means for moving one of said mop compressing members toward the other to operatively close said wringer, said other frame member being adapted to project beyond said hinge means to form a treadle for moving the aforesaid mop compressing member away from the other to open said wringer, and means on said first mentioned frame member for varying the amount of movement of said cam means.
8. In a mop wringer, a pair of frame members, means for pivotally hinging said frame members together, one of said members comprising means for simultaneously supporting the same in operative position upon the rim of a bucket and a bucket supporting surface and with said pivot means spaced from said surface, a mop compressing member carried by each frame member, treadle actuated cam means for moving one of said mop compressing members toward the other to operatively close said wringer, and means on said first mentioned frame member for varying the amount of movement of said cam means.
9. A mop wringer comprising a roller proximate one end of a frame, frame supporting means carried by the roller end of said frame for supporting the same upon the rim of a vessel, means carried at the other end of said frame for resting the same upon a supporting surface for the vessel, a second roller rotatably carried upon a second frame pivotally connected to the first named frame for contact with the first named roller, said second frame positioning the second roller in operative position with respect to the first named roller at substantially the same elevation as that defined by the rim of the vessel, and a force transmitting member carried by the second frame between the pivot and the roller carried by said frame, in combination with cam means carried by the first named frame for exerting a wringing force through said force transmitting member.
10. A mop wringer comprising a roller proximate one end of a frame, hook means proximate the roller end of said frame for resting the same upon the rim of a vessel and positioning said roller over the vessel at substantially the same elevation as that defined by the rim of the vessel, means carried at the other end of said frame for resting the same upon a supporting surface for the vessel, a roller proximate one end of a second frame, a pivot connecting said frames together and force transmitting means carried by one of said frames between said pivot and rollers to urge one of said rollers toward the other.

AARON WENGER.
